UNITED STATES PATENT OFFICE.

CORNELIUS R. UMBENHOWER, OF ANDERSON, INDIANA.

VAPOR OIL-BURNER.

1,329,446.

Specification of Letters Patent.

Patented Feb. 3, 1920.

Application filed October 21, 1919. Serial No. 332,227.

To all whom it may concern:

Be it known that I, CORNELIUS R. UMBENHOWER, a citizen of the United States, and a resident of Anderson, county of Madison, 5 and State of Indiana, have invented a certain new and useful Vapor Oil-Burner; and I do hereby declare that the following is a full, clear, and exact description thereof, reference being had to the accompanying 10 drawings, in which like numerals refer to like parts.

This invention relates to vapor oil burners and the like, and is an improvement on the invention shown in Patent No. 714,112, dated 15 November 18, 1902.

The object of this invention is to provide by the modification and rearrangement of parts and the addition of supplementary air vents for the complete combustion of the 20 fuel in the structure described in the before-mentioned patent.

Another object of the invention is to provide the burner with an improved deflector and heating plate for taking full advantage 25 of all the heat generated by the burning fuel, so that the same will not pass directly from the burner to the stove-pipe on the stove.

The full nature of this invention will be 30 understood from the accompanying drawings and the following description and claims.

In the drawings, which are made a part 35 of this application, Figure 1 is a central cross sectional view of the improved vapor oil burner. Fig. 2 is a plan view of the burner with the heating plate removed and other parts being broken away.

In the drawings 10 indicates a pipe leading 40 from any suitable supply of oil, such as kerosene or the like; 11 indicating a control valve and 12 an upwardly extending portion which is threaded at its upper end to receive a dome 13, the same having an 45 upwardly extending rim 14 concentric therewith and a discharge outlet 15 in the center thereof. The dome while hollow is rather thick and solid, especially in the upper portion so that it will hold considerable heat.

50 A supporting base plate 16 in the form of an annular ring with a central hollow opening 17 is provided with four inwardly projecting bracket arms 18 spaced at an equal distance from each other and suitably 55 notched or beaded to receive and support what may be termed an oil ring or oil pan

19, which is cylindrical and has an outer upwardly extending rim 20 and an inner upwardly extending rim 21 carrying a pipe-guide 22 through which the pipe 12 extends. 60 Air passages 23 are provided between the inner rim 21 and the pipe-guide 22 by the guide supporting portions 24. The oil ring 19 is also provided with a plurality of air openings 25 herein shown in the form of 65 tubes.

The outer rim of the ring 19 supports a cylindrical casing 26 herein shown in the form of a hollow truncated cone, the same having at its base an outwardly and downwardly extending portion 27 to seat on said casing. In the base of said truncated cone there are provided a plurality of passages or openings 28. Concentric with and supported by the casing 26 is an inverted 70 bowl-shaped hood 29 provided with a downwardly extending apron 30, the same being concentric with the oil ring 19 and being spaced therefrom to form an annular air passage therebetween. The hood 29 supports a combined heating plate and deflector 31, herein shown in the form of an inverted saucer with scalloped edges 32. In the central portion of said plate a plurality of vent holes or flame outlet openings 33 80 are provided. Secured to the inner side of said plate and depending therefrom are the supporting feet or brackets 34, the same resting upon the hood 29 to support the heating plate and having a tapering face 90 85 coöoperating with the contracted portion of the casing 26 to hold the heating plate centrally above the dome. The dome 13 and the cylindrical casing 26 forms an annular mixing and combustion chamber, 95 which receives air for combustion and vaporization through the air passages 28 in the lower portion of the casing and the air openings 25 and 23 in the oil ring. In addition to the before mentioned air passages 100 there are provided in the dome the openings 36, and registering therewith in the oil ring 19 are the openings 37, the same being connected by the air tubes 38.

From the foregoing description it will be 105 understood that there are provided a plurality of air passages for supplying air to the mixing chamber and the combustion area above the dome and below the heating plate; the first being the annular air passage between the casing and the hood and the passages 28 the central opening 17 and

the air passages 25 forming a second air passage, the central opening 17 and the air passages 23 forming a third source of supply, and the tubes 38 forming a fourth 5 means for supplying air to the mixing chamber, so that the oil is completely vaporized and burned. With this construction and as indicated by the arrows a better draft is obtained adjacent to the vaporizing portion 10 of the dome 13 and in the casing 26.

The operation of the device is similar to that shown in the patent herein before mentioned, the oil running down the dome 13 into the rim 14 and thence into the oil ring 15 19. The fuel is ignited by presenting a flame to the openings 33 or the combustion area beneath the combined heating plate and deflector. The burning fuel in the oil pan 20 will soon heat the upper end of the 20 pipe 12 and the dome 13 and be sufficiently heated to vaporize the oil as it passes out through the discharge opening 15. Through the air passages described oxygen is supplied to the flame and causes the fuel to be 25 completely vaporized and burned.

The invention claimed is:

1. An oil burner comprising means for supplying oil thereto, a dome having an outlet therein, a portion over which the oil 30 may flow including a rim, an oil pan beneath said dome and concentric therewith, said pan having a plurality of openings for the admission of air, a cylindrical casing concentric with and surrounding said dome and 35 having a plurality of air passages in its lower end, a hood concentric with said pan and casing and suitably spaced therefrom, said dome and pan having registering openings therein, and an air tube connecting said 40 registering openings.

2. An oil burner comprising means for supplying oil thereto, a dome having an outlet therein, a portion over which the oil may flow including a rim, an oil pan concentric with said dome and having a plurality of air openings therein, a supporting 45 base having an opening therein, a cylindrical casing concentric with and surrounding said dome and having a plurality of air 50 passages in its lower rim, a hood concentric with said pan and casing and suitably spaced from the same and the base, said dome and said pan having registering openings there-

in, and a tube connecting said registering openings and communicating with the opening in said base for supplying air to the burner. 55

3. An oil burner comprising means for supplying oil thereto, a dome having an outlet therein, a portion over which the oil may flow, including a rim, an oil pan beneath said dome and concentric therewith and having a plurality of tubes for the admission of air, a cylindrical casing supported by said pan and concentric therewith and having 60 a plurality of air passages in its lower end, a hood concentric with said pan and casing and suitably spaced therefrom to provide an annular air passage, a supporting base having a central opening therein, said tubes 65 communicating with said opening, a deflector suitably positioned above said dome and supported by said hood, said dome and said pan having a plurality of registering openings therein, and a plurality of tubes 70 connecting said registering openings and communicating with said central opening. 75

4. An oil burner including in combination a dome having an outlet therein, a cylindrical casing surrounding said dome 80 and concentric therewith, a hood concentric with said casing, a deflector supported above said dome and being of greater diameter than any of the before mentioned parts, said deflector having a downwardly extending 85 rim, said deflector further having a plurality of depending bracket feet to rest upon said hood.

5. An oil burner including in combination a dome having an outlet therein, a 90 cylindrical casing surrounding said dome and concentric therewith, a hood concentric with said casing, a deflector supported above said dome and being of greater diameter than any of the before mentioned parts, said 95 deflector having a downwardly extending rim with scalloped edges and a plurality of openings in the central portion thereof, said deflector further having a plurality of depending bracket feet to rest upon said 100 hood, and said feet having cam-shaped faces for engaging the casing and centering the deflector centrally of said burner.

In witness whereof I have hereunto affixed my signature.

CORNELIUS R. UMBENHOWER.
